(57) **CLAIM**

The ornamental design for a striker for a latch, as shown and described.

DESCRIPTION

FIG. 1 is a front isometric view of the striker for a latch; FIG. 2 is a rear isometric view of the striker for a latch of FIG. 1;

FIG. 3 is a plan view of the striker for a latch of FIG. 1; FIG. 4 is a front view of the striker for a latch of FIG. 1; FIG. 5 is a rear view of the striker for a latch of FIG. 1; FIG. 6 is a side view of the striker for a latch of FIG. 1; and, FIG. 7 is an opposite side view of the striker for a latch of FIG. 1.

The broken lines, if any, depict portions of the article that form no part of the claimed design.

The surface shading and/or surface lines with breaks, if any, illustrated in the figures is provided merely to highlight the contour of the design and it is not intended to be illustrative of texture or gloss.

1 Claim, 7 Drawing Sheets
